UNITED STATES PATENT OFFICE.

WARREN P. FREEMAN, OF NEW YORK, N. Y., ASSIGNOR TO THE EMPIRE ELECTRICAL MACHINERY COMPANY, OF SAME PLACE.

DESIGN FOR A FIELD-MAGNET FRAME.

SPECIFICATION forming part of Design No. 31,238, dated July 18, 1899.

Application filed April 10, 1899. Serial No. 712,562. Term of patent 14 years.

To all whom it may concern:

Be it known that I, WARREN P. FREEMAN, a citizen of the United States, and a resident of New York, in the county of New York and State of New York, have invented and produced a certain new and useful Design for Field-Magnet Frames, of which the following is a specification, reference being had to the accompanying drawings, forming part of the same, in which—

Figure 1 is a side elevation of my newly-designed field-magnet frame, and Fig. 2 is a rear elevation thereof.

The body of the frame I have designed is upon the outer surface substantially for the greater part of its length in the form of the outer surface of a cylinder divided into two equal sections by slots in the sides running from end to end. Toward the rear end I curve the faces toward the axis of the cylinder. For a distance from the forward end the frame is hollow, and near the rear end there is a cross-piece extending from the inner side of one section of the cylinder to the opposing inner side of the other section of the cylindrical part, the lines of said cross-piece being well within the side lines of the cylindrical parts and also within the lines bounding the front

and rear ends of the article, the front line of the cross-piece being between the two ends of the magnet.

The main features are the cylinder-like body with oppositely-located openings running lengthwise thereof, a hollow extending inward from the forward end and partially bounded by the opposing partial cylinder-like sections, and a cross-piece within the exterior lines of the cylinder-like sections extending from the inner side of one section of the cylindrical part to the inner side of the opposing section of the cylindrical part, its front line located well back of the forward end of the article and reaching from about the rear end of the forward hollow part well toward the rear end of the frame.

What I claim as my invention, and desire to secure by Letters Patent, is—

The design for a field-magnet frame substantially as herein shown and described.

Signed at New York, in the county of New York and State of New York, this 21st day of March, A. D. 1899.

WARREN P. FREEMAN.
